CONTAINER AND METHOD OF SEALING
SAME

Pasquale V. di Cosmo, Phillipsburg, N. J., assignor to The Canister Company, Phillipsburg, N. J., a corporation of New Jersey

Application December 3, 1942, Serial No. 467,805

1 Claim. (Cl. 229—5.5)

This invention relates to containers, receptacles or the like capable of being formed entirely of fibrous material and particularly to methods and means for constructing the ends of such containers to provide a strong, liquid-tight and airtight seal therefor.

While my invention is capable of use in packaging, storing and shipping almost any kind of material in solid, pulverized, paste or liquid form, the type of container hereafter particularly described and shown in the drawing is especially designed for the storage and shipment of oils, paints and similar oily liquids.

Heretofore, it has been common practice to ship and store oils and paints in metal cans or containers. This generally has been necessary because of the solvent and penetrating characteristics of oils and the difficulties involved in producing and maintaining an adequate seal between the elements of which non-metallic containers have been made. One very satisfactory form of container formed in part of fibrous material and designed for use with oil is shown and described in the patent to Kernahan No. 2,202,558. However, the end members of such containers are formed of metal and are crimped or spun onto the body of the container, requiring operations and material which are relatively expensive and which, at present, are difficult to obtain. Another type of container, which may be made entirely of fibrous materials, and which may be used with oily liquids is shown and described in the copending application of di Cosmo et al. Serial No. 447,726, filed June 19, 1942. This construction also is very satisfactory but requires numerous manufacturing steps and operations which increase the cost of the finished container.

In accordance with the present invention a container, which preferably is formed entirely of fibrous materials, is produced by operations which are very simple and inexpensive and yet the strength of the container and the effectiveness of the seal produced are increased. These results are attained by providing the container, and particularly the filling end thereof, with a sealing diaphragm formed of oil and grease resistant paper or the like and arranged to permit the container to be filled while protecting the sealing surfaces thereof. In combination with the sealing diaphragm there is used a closure member which cooperates with the diaphragm to insure the formation of a liquid-tight and air-tight end construction on the container. Moreover, the construction serves to shield the body of the container and all porous elements thereof from the oil or

other material in the container so that weakening or deterioration of porous portions of the body and closure member are prevented and preservation of the desired seal is assured.

5 One of the objects of the invention is to provide a novel form of container capable of being formed entirely of fibrous material by simple and economical operations.

Another object of the invention is to provide 10 a fibrous container which is liquid-tight and airtight and which is so formed that it serves to protect all porous portions of the container from the action of oils or liquids which might weaken the construction or impair the sealing of the container.

15 A further object of the invention is to provide a container formed of fibrous material with a sealing diaphragm and end closure of novel construction and arranged to protect the sealing surfaces of the container from oil or other material which might impair the seal.

20 These and other objects and features of the invention will appear from the following description thereof in which reference is made to the figures of the accompanying drawing.

25 In the drawing:

Fig. 1 is a perspective showing the end of a container and the sealing diaphragm in a preferred form of container embodying the present invention and in the position they assume in assembly,

30 Fig. 2 is a view similar to Fig. 1 showing the sealing diaphragm applied to the container and the closure member in position for application,

Fig. 3 is a vertical sectional view of the construction shown in Figs. 1 and 2 with the closure member applied to the container, and

35 Fig. 4 is a view similar to Fig. 3 with the closure member permanently secured in place.

In that form of container shown in the drawing the body 2 is cylindrical in shape and preferably 40 is formed of spirally wound fibrous material, such as chipboard, kraft paper or other paper-like material. The body is provided with an inner liner formed of oil and grease resistant material 4 such as paper or parchment, as described and claimed 45 in the Kernahan patent referred to above. A sealing compound which may be an oil insoluble glue, is applied to the end of the container body so that the glue initially extends further downward from the end of the container on the inside 50 thereof as shown at 6 than on the outside of the container as shown at 8.

The sealing diaphragm is formed of oil and 55 grease resistant material, such as the parchment paper 4 which lines the container. Before being

applied the diaphragm is in the shape of a flat ring of material 10, shown in Fig. 1, having a central opening 12 which in the finished container serves as a filling opening through which the oil or other material may be charged into the container. Such rings can be readily and economically cut from flat sheets of the parchment paper in a single operation and need not be further formed or treated before being applied to the body of the container.

The outer edge 14 of the ring is of substantially greater diameter than the container whereas the inner edge 16 thereof is of substantially smaller diameter than the container. The sealing diaphragm is preferably applied and simultaneously shaped to conform directly to the body of the container by means of a die. During this operation the central portion 20 of the sealing element is pushed into the end of the body beyond the rim 18 thereof while the outer portions of the sealing diaphragm are pressed against the adjacent glue bearing portions 6 and 8 of the body and about the rim 18. The central portion 20 of the diaphragm then is located below the rim of the container in the position shown in Fig. 2 and extends inward from the body at right angles thereto forming an annular flange that serves as a support for the closure member subsequently applied and serves as a shield or splash guard during the operations of filling, conveying and sealing the container.

It will be evident that as the portion 20 of the diaphragm is pushed into the end of the container body and passes beyond the rim 18 thereof the portion 22 of the diaphragm which lies directly adjacent the inner surface of the container and above the flange 20 will be pressed against the glue 6 and will wipe over the glue spreading it and causing it to flow into the folds and crevices formed in the diaphragm as it is shaped to the container body. At the same time the glue will be spread over the inner face of the body so that the portion 22 will be firmly and intimately bonded to the container and all crevices therein will be sealed. The outer marginal portion 24 of the diaphragm is also pressed downward about the outer surface of the container and against the glue 8 so as to be securely held in place. The wiping action resulting from relative movement of the portion 22 of the diaphragm with respect to the inner surface of the body also serves to cause the glue 6 to be squeezed downward from the upper rim 18 of the container body forming a continuous sealing film of glue between the body and the diaphragm. Moreover, that portion of the glue which collects at the joint between the inwardly extending flange 20 and the inner surface of the container body spreads circumferentially about the joint and flows together into a continuous sealing gasket of glue which serves to close any pin holes or crevices formed by wrinkling of the diaphragm during the forming operation. This sealing gasket, as shown at 28 in Fig. 3, presents a smooth, unbroken surface of a permanent liquid-tight and air-tight character. The flowing and spreading of the glue may be aided by using a heated die whereby the glue is softened sufficiently to insure ready flow thereof over the surfaces and into all pores and crevices as well as fluxing thereof into the continuous sealing gasket 28.

The opposite end of the container may be closed and sealed by any suitable construction. The preferred type of closure means applied to the opposite end of the body is that shown and

described in the copending application of di Cosmo Serial No. 467,804 filed December 3, 1942. When one end of the container body is closed and the sealing diaphragm 10 is applied to the other end thereof the container is placed with the latter end upward so that it presents the central filling opening 12 surrounded by the inwardly extending flange 20. The empty containers may then be conveyed to filling and closing devices and may be handled in the same manner as ordinary tin cans or other receptacles. During the conveying, filling and closing operations the containers are necessarily jostled, jolted and vibrated to some extent, but the flange 20 effectively prevents oil or other liquid from splashing upward onto the upper surface of the flange or onto the portion 22 of the sealing diaphragm which are subsequently used as sealing surfaces in the final closing and sealing operation. These surfaces are thus protected and preserved in a clean condition so as to be receptive to the glue or sealing compound employed.

The closure member shown at 30 in Fig. 2 is formed of a disc 32 of chipboard or other stiff, fibrous material, and is provided with an inner lining 34 of oil and grease resistant paper such as that used in forming the sealing diaphragm 10 and the liner 4 for the body of the container. The disc 32 is circular in form and substantially equal in diameter to the internal diameter of the container body so as to have a snug or tight fit therewith when forced down against the flange 20. The marginal portion 36 of the lining 34 extends beyond the edges of the disc 32 and therefore when the closure is applied the portion 36 turns upward adjacent the portion 22 of the sealing diaphragm which lies adjacent the inner wall of the container body above the flange 20. The cut and porous edges of the disc 32 are thereby covered and protected by the oil resistant liner whereas the added thickness of the liner portions 36 aids in forming a tight wedging fit between the closure and the body.

The closure member is readily formed by stamping or cutting the stiff discs and the larger lining members 34 from flat sheets and they are thereafter assembled by simply gluing the lining member to the disc with the disc centered on the lining member.

In applying the closure and sealing it in place, glue is applied to the upper face of the flange 20 adjacent the corner where it meets the upwardly extending portion 22 of the sealing diaphragm, as shown at 38. Some glue also may be spread upward from the corner over the portion 22 of the sealing diaphragm. The closure member 30 is then forced down against the flange 20 so that the glue is caused to flow upward along the face 22 of the diaphragm and over the upwardly folded marginal portion 36 of the lining 34 of the closure. Some of the glue also flows inward over the surface of flange 20 to provide a continuous seal between the flat upper surface of the flange and the flat lower face of lining 34. In this way a complete and tortuous seal is provided about the edges of the closure, establishing an air-tight and liquid-tight joint between the closure member and the sealing diaphragm.

The closure member preferably is applied by means of a die, which may be heated, and which is formed to force the closure member down into firm seating engagement with the flange 20 and slightly below the upper extremity of the rim 18 of the container body as shown in Fig. 3. The die preferably also is formed so that it will turn

the rim 18 inward over the marginal edge of the closure member as shown at 40 in Fig. 4. This operation may be performed by the same die that moves the closure into place so that both operations are performed as a single step in closing and sealing the container. The closure is thereby positively secured in place by structural means in addition to the glue.

As will be readily seen in Fig. 4 the closure member in the finished and sealed container is supported from below by the flange 20 and the marginal gasket of glue 28, whereas it is secured at the edges by the frictional contact and glue between the surfaces 22 and 36 and is further clamped and held in position by the inwardly turned bead 40 formed by molding of the rim 18 of the container body. Moreover, the continuity of the sealing member in extending upward adjacent the inner face of the body, over the rim 18 and downward about the outer surface of the container body adds materially to the strength of the support afforded for the closure member. The structure thereby provided is exceedingly strong, while all joints are fully and completely sealed and the cut edges of the fibrous body are covered and protected by oil resistant paper layers. Such containers are capable of withstanding severe usage and may be filled, sealed, stored and shipped as easily and readily as conventional tin cans or containers.

In finishing the container a label or similar outer paper wrapper 42 is applied to the filled containers and extends over the downwardly turned marginal edges 24 of the sealing element to provide a neat finished appearance to the container and to protect said edges from being accidentally torn or raised by engagement with some other container or object.

The sealing compound referred to as "glue" in the foregoing description may be an ordinary fish glue or animal glue or have any other suitable composition capable of resisting oil. However, the composition preferably is thermo-plastic in character so that when heated dies are used it flows readily into all cracks, crevices and interstices to provide a most effective seal. When the material with which the container is filled is a liquid other than an oily substance the sealing compound may be an asphalt or resinous composition or it may be rubber, latex or any other

substance resistant to the action of the contents and capable of forming an adequate seal. Similarly the liner 4, sealing diaphragm 10 and closure lining 34 may be formed of metal foil, Cellophane, or other sheet material which will not deteriorate under the conditions of use and the linings may be applied to the container body and closure as separate operations by laminating or they may be applied as a film or solution, by spraying, dipping or otherwise to provide a coating which will seal the relatively porous material or fibrous stock from which the body and closure disc are formed and be resistant to the contents of the container.

These and other modifications and changes may be made in the composition, form and arrangement of the elements from which the container is formed and in the methods of assembling and sealing the same in producing a finished container. In view thereof it should be understood that the particular embodiment of the invention shown in the figures of the drawing and herein described is intended to represent a preferred form thereof and is not intended to limit the scope of the claims.

I claim:

A container comprising a fibrous body having an oil resistant lining, a fibrous closure member applied to the container body and having an oil resistant lining, and an oil resistant sealing diaphragm located between the container body and closure member and presenting an inwardly extending flange positioned directly below the closure, the lining for said closure member being of larger diameter than the closure member and being turned outward about the marginal portions of the closure member to protect the same, and cooperating with said sealing diaphragm to seal the container, there being a sealing compound located between the sealing diaphragm and the lining of the container body and between the sealing diaphragm and the lining of the closure member providing a permanent air-tight and liquid-tight seal between the parts mentioned, the rim of the container body extending inward over the marginal portion of the closure member and being of such stiffness as to hold the closure member permanently in engagement with said flange.

PASQUALE V. DI COSMO.
